UNITED STATES PATENT OFFICE.

VINCENC KRAJIČEK, OF PARDUBITZ, AUSTRIA-HUNGARY.

T-SQUARE.

970,625.

Specification of Letters Patent. Patented Sept. 20, 1910.

Application filed October 11, 1909. Serial No. 522,099.

To all whom it may concern:

Be it known that I, VINCENC KRAJIČEK, commercial traveler, a subject of the Austro-Hungarian Emperor, and resident of 767 5 Sladkovskystrasse, Pardubitz, Bohemia, Austria-Hungary, have invented an Improved T-Square, of which the following is a specification.

This invention has for its object to combine the auxiliary means which are necessary for drawing angles of given size, with the T-square in such a way that they form a handy whole with the latter.

The invention consists substantially in a 15 second rule being combined with the blade of the T-square, which second rule is intended to replace the ordinary triangle or other set square, and for this purpose is arranged so as to be revoluble over a circular 20 scale and also adapted to slide along the blade of the T-square.

An example of construction of the invention is shown in the accompanying drawings, in which:—

25 Figure 1 is a plan view; and Fig. 2, a section on the line A—B of Fig. 1.

The blade 1 of the T-square is provided with a longitudinal slot 2 which serves for guiding a slide piece 3. A disk 4 is firmly 30 connected with the latter and between the slide piece 3 and the disk 4, a rule 5 is provided said rule 5 being pivoted on the sliding piece 3. The disk 4 is provided with a

circular scale, of which only some divisional lines are shown, while the rule 5 is provided with a gage mark 7. This in combination with the dial or divided circle 8 allows of the rule 5 being adjusted to make any desired angle with the blade 1. A pointer or indicator 9 is provided on the upper side of the disk 4 the said pointer being pivoted on the pin 6, which pointer may be adjusted to a division 10 of the blade 1. This allows of parallel lines being drawn with the rule 5 at a given mutual distance apart 45 without separate instruments, such as compasses or the like, being necessary.

Having fully described my invention, what I claim and desire to secure by Letters Patent is:

In an improved T-square, the combination of a graduated blade having a longitudinal slot, a piece adapted to slide in the slot, a graduated disk secured to said piece, a rule pivoted on said piece and interposed between the latter and the disk, a pin carried by the disk, and a pointer carried on the pin, substantially as described and shown and for the purpose set forth.

In testimony whereof I have hereunto set 60 my hand in the presence of two subscribing witnesses.

VINCENC KRAJIČEK.
